(57) **CLAIM**

The ornamental design for a display screen or portion thereof with graphical user interface, as shown and described.

DESCRIPTION

FIG. 1 is a front view of a display screen or portion thereof with graphical user interface embodying the new design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; FIG. 7 is a seventh embodiment thereof; and, FIG. 8 is an eighth embodiment thereof. The outermost broken line illustrates a portion of a display screen while all other broken lines illustrate elements of a graphical user interface or representative imagery. All broken lines form no part of the claimed design.

1 Claim, 8 Drawing Sheets

FIG. 3

FIG. 4

FIG. 7
